CIRCUIT FOR AMPLIFIER TUBES

Application filed March 18, 1925. Serial No. 16,345.

- This invention relates to vacuum tube devices. More particularly, it relates to a vacuum tube system in which provision is made for preventing the tubes from oscillating. It is an object of this invention to avoid the loss of sensitiveness heretofore caused in such systems by currents of a frequency above that at which the tuned circuit is intended to operate. Such oscillations of higher frequencies are ordinarily termed "parasitic" currents. They are usually caused by the presence of harmonics in an oscillating circuit. They may, however, arise from other causes, some of which are described below. It is a further object of this invention to provide an absorption circuit in connection with each tuned circuit where such parasitic currents are likely to occur. The parasitic currents if allowed to occur are likely to block the tube completely or at least render it less sensitive. In the system to which this invention is preferably applied, an oscillating circuit is provided comprising an inductor and a condenser in parallel. The inductor has a tap at a point intermediate its ends. Theoretically, for the best operation of the system, the magnetic coupling between the two parts of this coil on opposite sides of the tap should be 100%. Such complete coupling is impossible and the incompleteness of the coupling tends to produce an oscillation which is of considerable amplitude and usually paralyzes the amplifier tube, because of relatively large alternating current voltage impressed on its grid. It is a further object of this invention to prevent oscillations of this parasitic frequency from being developed. My invention is preferably used with a receiving set having several stages of radio-frequency amplification, each of said stages having a tuned grid circuit and also a neutralizing condenser. The condenser prevents the regeneration from becoming sufficient to cause the tubes to oscillate. It is a further object of my invention to provide, in each of said stages, an absorption circuit which will counteract any tendency to parasitic oscillations due to the fact that the two parts of the inductor in the grid circuit are not perfectly coupled. It is a still further object of my invention to make the tuning of the absorption circuit broad, thereby providing for the differences in frequency of the parasitic oscillations in different sets. The breadth of the tuning of the absorption circuit also prevents beat notes which might otherwise arise from the interaction of two frequencies, one impressed on the tuned circuit by the received energy and the other due to the response of the tuned circuit thereto. The broad tuning of the absorption circuit also prevents periodic interchange of energy between it and the tuned circuit which might give rise to noises in the tubes. Other objects of my invention and details of the construction will be apparent from the following description, when read in connection with the accompanying drawing, wherein The single figure is a diagram of the circuits and apparatus constituting a radio receiving system in which a preferred form of my invention is applied. The antenna 1 is connected by the switch 2 to the inductor 3, either directly or through the condenser 4. The mid point of the inductor 3 is connected to ground through the condenser 5. The inductor 3 is shunted by an adjustable condenser 6, the inductor and condenser together constituting a tuned circuit which forms part of the grid circuit of the vacuum tube 7. The plate circuit of the tube 7 includes the primary 8 of a transformer connecting the radio-frequency stage including the tube 7 in cascade with the stage including the tube 9. A battery 11 is in series with the primary coil 8. The connection from this battery to the filament of the tube 7 is made by means of a shield, represented by the ground 12. A condenser 13 is shunted about the battery 11. This is represented in the drawing by showing the condenser as connected to the ground 14, which, in practice, would be the same shield. The ground 15 is associated with the

filament heating circuit including the battery 16 and the rheostat 17.

The secondary 18 of the inter-stage transformer is shunted by an adjustable condenser 19. The tuned circuit 18-19 is a part of the grid circuit of the tube 9. A conductor joins the mid-point of the secondary 18, in the stage of radio-frequency amplification including the tube 9, and the mid-point of the inductor 3, in the stage including the tube 7.

The plate circuit of the tube 9 includes the primary coil 20 of a transformer connecting this stage to the next stage. The next stage may, if desired, include another amplifier, but, as illustrated, it comprises the tube 21 which is a detector. It will be obvious, however, that as many stages of radio-frequency amplification as are necessary may be introduced ahead of the detector.

In each of the amplifier stages, a condenser is introduced between the oscillating or tuned circuit and the plate circuit. Preferably, this condenser is connected to that side of the oscillating circuit which is remote from the grid and that side of the plate-circuit inductance which is adjacent the plate. Thus the condenser 22 is connected to the upper terminal of the primary coil 8 as illustrated and to the lower terminal of the inductor 3 and condenser 6. Likewise, the condenser 23 is connected between the upper terminal of the primary coil 20 and the lower terminals of the secondary 18 and the condenser 19.

The detector tube 21 has in its grid circuit a condenser 24 shunted by a resistor 25, constituting a grid biasing device. The filament of this tube is connected to the secondary 26 of the transformer between tubes 9 and 21. The point at which this connection is made is preferably intermediate the ends but not necessarily the middle of the secondary 26. It is so chosen that the impedance between the grid of the tube 21 and the filament shall cause minimum losses.

The connection to the secondary 26 does not include any "C" battery, because the necessary bias is provided by the condenser 24 and resistor 25. The other tubes are each biased by the common "C" battery 27, which is shown as connected between the ground 28 and the conductor connecting the mid-points of inductor 3 and secondary coil 18. It will, however, be obvious that the battery 27 may be connected between the ground and any other point of the system of conductors extending to the several grids. The grid circuit of the detector tube 21 is tuned by means of a condenser 29 in shunt with the secondary coil 26.

Preferably, provision is made for operating the filament of the tube 21 at a different temperature from that of the amplifier-tube filaments. Therefore, a rheostat 30 is provided which controls the current through this filament only, the current through the

other filaments being controlled by the rheostat 17.

The plate circuit of the detector tube includes the primary coil 31 of an audio frequency transformer and a portion only of the battery 11. In order that a shunt for the high frequency currents may be provided about this part of the battery, a condenser 32 is provided between the shield and the terminal of the coil 31 nearest the plate. The secondary of the audio-frequency transformer is connected to the grid of the tube 33 and to the negative side of the battery 27. The plate circuit of the tube 33 includes a telephone 34 or other translating device and the whole of the battery 11. Preferably the telephone 34 is shunted by a condenser 35.

In the operation of the device, signals are received upon the antenna 1 and cause the circuit 3-6 to oscillate. This circuit is tuned to the frequency of the incoming signals. The oscillations thereof are amplified by the tube 7 and repeated in the primary 8. Any tendency of the tube 7 to oscillate at the working frequency because of the inductive reactance of its plate circuit, is neutralized by the condenser 22 and the divided coil 3.

The coupling between the two parts of the coil 3 is not 100%. If it were, the coil would present no reactance to the electromotive force impressed thereon through the grid-plate capacity of the tube 7, at one end of the coil 3, and through the condenser 22 at the other end thereof. The oscillation of this coil, if the coupling were perfect, would, therefore, be determined wholly by the incoming signal and the tuning effect of the condenser 6. The form of the oscillations in the coil 3 under these conditions can be described with a fair degree of exactness as a voltage loop extending the length of the coil. The frequency of these oscillations is determined mainly by the constants of the circuit 3-6. The distributed capacity of the coil 3 plays but little part in this determination.

On the other hand, when the coupling between the two halves of the coil 3 is imperfect, the disturbances in the grid circuit consequent upon the inductive character of the plate circuit will not be wholly neutralized by the connections including the condenser 22. These disturbances tend to set up parasitic oscillations of a very high frequency. The parasitic oscillations can be approximately represented by two voltage loops, the voltage node between them being at or near the middle of the coil.

For very high frequencies, the condenser 6 is practically a short circuit. The two halves of the coil 3, can, therefore, be regarded as connected in parallel and the two capacities, namely, the grid-plate capacity of the tube 7 and the capacity of the condenser 22, may also be regarded as connected in parallel.

The parasitic oscillations have their frequency determined mainly by the distributed capacity of the two halves of the coil 3 and by the leakage inductance, which the half-coils possess because the coupling between them is not perfect. All of these reactances being very small, the frequency of these oscillations is high. It is, therefore, easy to selectively tune a circuit, whereby it will not be resonant to currents of the signalling frequency, but will absorb oscillations of the parasitic frequency. The difference between the parasitic frequency and the signalling frequency will even permit the absorption circuit to be so broadly tuned that it will provide for manufacturing tolerances and prevent the tube noises explained above.

The coil 41 and the condenser 42 are designed to constitute such a selective absorption circuit for the stage of the tube 7. A resistance 43 is provided in circuit with the inductor 41 and condenser 42. The absorbing effect of this circuit can be adjusted by varying the coupling of said circuit and coil 3. An approximate tuning of the absorption circuit may be provided by correctly choosing the magnitude of the inductance and capacity. The magnitude of the resistance 43 serves to determine the degree of damping. It is desirable that this damping be no greater than just sufficient to prevent the development of oscillations of the various parasitic frequencies. Although the resistance 43 is illustrated as a separate element, it will ordinarily be provided by selecting wire of the desired resistance for the coil 41.

Similarly, an inductor 46, a condenser 47, and a resistance 48 may be provided in connection with the amplifier tube 7. If more than two stages of radio frequency amplification are employed, a similar absorption circuit may be provided for each stage.

Other applications of the means herein disclosed for preventing parasitic oscillations will readily occur to those skilled in the art. The specific illustration and description of a single application is not intended to restrict the invention. No limitation is intended other than such as are required by the prior art or indicated in the accompanying claims.

I claim as my invention:

1. In a radio device, a tunable circuit having provisions for preventing feed-back over the tuning range thereof, and absorption means for preventing parasitic oscillations therein at frequencies above said range.

2. In an amplifier, a plurality of stages, a vacuum tube in each stage, an oscillation circuit in the input of each tube, said circuits being tunable to the same frequency, and absorption circuits, one for each of said tunable circuits, each of said absorption circuits being tuned to a frequency substantially the same as that of a predominating parasitic

frequency of the stage with which the said absorption circuit is associated.

3. In an amplifier, a plurality of stages, a vacuum tube in each stage, an oscillation circuit in the input of each tube, said circuits being tunable to the same frequency, and absorption circuits, one for each of said tunable circuits, each absorption circuit being tuned to a frequency several octaves above any frequency to which its associated oscillation circuit is intended to be tunable, said higher frequency being the predominant parasitic frequency of the stage with which the absorption circuit is associated. 75

4. In an amplifier, a tunable amplifying stage, means for preventing said stage from oscillating at frequencies within the range over which it is designed to be tunable, and an absorption circuit, for said stage, said absorption circuit being tuned to a predominant parasitic frequency of its associated stage, which frequency is above said range. 80

5. In a radio device, a triode, a grid circuit, a plate circuit, an inductor in one of said circuits, means connecting a mid-point 90 of said inductor with a point common to both circuits, and tuned absorption means associated with said inductor for preventing parasitic oscillations therein at ultra high frequencies. 95

6. In a radio device, a triode, a grid circuit, a plate circuit, means for tuning one of said circuits, an inductor in one of said circuits, means connecting a mid-point of said inductor with a point common to both circuits and tuned absorption means associated with said inductor for preventing parasitic oscillations therein at frequencies above the tuning range, and a device between said circuits for preventing oscillations at the frequency for which one of the circuits is tuned. 105

In testimony whereof, I have hereunto subscribed my name this 14th day of February, 1925.
